CLAIM

The ornamental design for a cutting tool with multiple scissors, as shown and described.

DESCRIPTION

FIG. 1 is a perspective view of a cutting tool with multiple scissors of the present invention;

FIG. 2 is a top view thereof;

FIG. 3 is a first side view thereof;

FIG. 4 is a bottom view thereof;

FIG. 5 is a second side view thereof;

FIG. 6 is a first end view thereof;

FIG. 7 is a second end view thereof;

FIG. 8 is a perspective view thereof, where the first scissors tool is shown in an operational position and the remaining scissors tools are shown in a stored position;

FIG. 9 is a perspective view thereof, where the second scissors tool is shown in the operational position and the remaining scissors tools are shown in the stored position;

FIG. 10 is a perspective view thereof, where the third scissors tool is shown in the operational position and the remaining scissors tools are shown in the stored position;

FIG. 11 is a perspective view of the cutting tool thereof, where the fourth scissors tool is shown in the operational position and the remaining scissors tools are shown in the stored position;

FIG. 12 is a perspective view of thereof, where the fifth scissors tool is shown in the operational position and the remaining scissors tools are shown in the stored position; and,

FIG. 13 is a perspective view thereof, where the sixth scissors tool is shown in the operational position and the remaining scissors tools are shown in the stored position.

The ornamental design which is claimed is shown in solid lines in the drawings. Any broken lines in the drawings are for illustrative purposes only and form no part of the claimed design.
